APPLICATION OF ADHESIVE

Carl A. Newhall, Peabody, Mass., assignor to
 United Shoe Machinery Corporation, Paterson,
 N. J., a corporation of New Jersey

Application July 5, 1934, Serial No. 733,707

21 Claims. (Cl. 12—80)

This invention relates to the application of an adhesive to a piece of work, such as a shoe part, and is particularly concerned with a machine by means of which such an application of adhesive 5 may be effected. In Letters Patent of the United States No. 1,970,257, granted Aug. 14, 1934, upon an application of M. W. Tetlow, concerning Methods of securing together shoe parts and the like, there is described a procedure in accordance with 10 which a piece of textile material containing a cellulose derivative (for example a cellulose ester such as cellulose acetate) is applied in the desired position upon a piece of work and the cellulose derivative is converted into an adhesive by a solvent applied to that material. The machine 15 illustrated herein is adapted to carry out one or more steps of that method and an object of the invention is to provide a machine by means of which the Tetlow method may be carried out 20 expeditiously and the material applied accurately in the desired position.

As set forth in the Tetlow patent to which I have just referred, it has been usual in attaching soles to shoes by means of pyroxylin cement to 25 coat the overlasted marginal portions of the shoe uppers with the adhesive and to coat the marginal portion of the attaching surfaces of the soles. These coatings of cement are then allowed to dry and later, just as the soles and shoes are 30 to be brought together, it is usual to activate the cement with a suitable softener or solvent. It will be seen that this method of procedure involves the application of at least three separate 35 coatings, each by a separate operation. It is proposed, therefore, in the Tetlow patent to apply to only one of the shoe parts a fibrous textile material, the fibers of which consist of a cellulose derivative which is softened and converted into an adhesive by means of a suitable solvent for 40 the cellulosic fibers. The two shoe parts are then immediately brought together without allowing the adhesive to dry. The method is highly 45 advantageous not only because it eliminates two operations but also because it provides for accurately measuring the amount of cement and insures the uniform distribution of adhesive over the area to be coated, at the same time enabling the positioning of the band of adhesive to be carried out readily.

50 The illustrated machine, in accordance with features of the invention, provides for the application of such a piece of textile material progressively to a piece of work. While it is recognized that the piece of textile material may be in 55 the form of tape, braid or other preformed fabric,

the illustrated machine is constructed and arranged to apply a plurality of parallel strands of loosely woven yarn. Cellulose acetate yarn, commonly known as "acetate silk," has been found to be a suitable material which is readily 5 obtainable. Accordingly, the material will hereinafter be referred to as acetate silk without intending thereby to limit the claims or to suggest that this is the only material which may be employed.

10 Other features of the invention reside in improved mechanism for feeding the work, progressively pressing in the desired position thereon a band of acetate silk and for substantially simultaneously securing the acetate silk to the 15 work, and converting it into an adhesive. As illustrated, the machine is arranged to apply a viscous type of solvent to the work in advance of the application thereto of the band of acetate silk and in a position where it will underlie said 20 band and also to apply to the upper surface of the band a solvent of a low-viscosity type. The solvent of viscous type is employed not only to convert the cellulosic fibers but also to serve as an adhesive thereby quickly to secure the acetate 25 silk in the desired position on the work. The low-viscosity solvent serves to facilitate the rapid conversion of all the fibers into an adhesive which will be substantially immediately available for the attachment, for example, of a shoe sole to the 30 bottom of a previously lasted shoe.

Still another object of the invention is to provide an improved method of applying an adhesive to a piece of work. In one aspect, the method consists in progressively and repeatedly hammering 35 into contact with the work a piece of textile material containing a cellulose derivative which has been treated with a solvent. The method contemplates the use of a narrow strip of material which may readily be distorted in all directions.

In another aspect, the method consists in securing to a piece of work such a strip of textile material by means of an adhesive and applying to the textile material a solvent for the cellulose derivative contained therein. Preferably, the adhesive will also contain a solvent for the cellulose derivative.

These and other features of the invention will now be described in the following specification, 50 reference being had to the accompanying drawings, in which

Fig. 1 is a side elevation of the machine;

Fig. 2 is a detail in section through the yarn grippers of the pull-off mechanism;

Fig. 3 is a vertical section taken on the line III—III of Figs. 6 and 10;

Fig. 4 is a detail view showing the feed foot;

Fig. 5 is an end elevation of the head of the machine;

Fig. 6 is a horizontal section on the line VI—VI of Fig. 5;

Fig. 7 is a rear elevation of the head of the machine showing particularly the resetting and release mechanism for the cut-off knife;

Fig. 8 is a fragment showing the pull-off mechanism in operation;

Fig. 9 is a plan on a large scale showing the relation of the presser foot and the presenter to a shoe sole;

Fig. 10 is a horizontal section on the line X—X of Fig. 5, and

Fig. 11 is an end elevation, on a large scale, of that portion of the head of the machine which is near the work.

The machine provides for the progressive feeding of a piece of work, such as a sole, and the continuous application to the margin of the work of a series of strands of acetate silk yarn fibrous by nature, which are stuck in position on the sole and are treated by a solvent to transform the yarn into a cement which may be utilized for attaching the sole to a shoe. At the end of the operation upon a piece of work, the strands of yarn are cut off and the unused ends of the yarn are caused to stick out beyond the presenting mechanism to facilitate their attachment to the succeeding piece of work.

The machine comprises a frame 10 having a hollow overhanging arm 12 and a supporting arm 14 upon which is mounted a work table 16. Projecting through a slot in this table is an idle work supporting roll 18 and on the table is mounted an edge gage 20. The edge gage 20 is provided with two humps or bulges 22 and 24 (Fig. 9) against which the work rests and with which it coats in the same manner as a similar gage described in an application Serial No. 692,307, filed October 5, 1933 in my name, relating to machines for applying activating liquids to cemented shoe parts. An overhanging flange 26 (Fig. 7) on this gage, turned up at 27 (Figs. 5 and 9) to facilitate entering a new piece of work, assists in holding the work against the table. The general arrangement of the work feeding mechanism is similar to that illustrated in Letters Patent of the United States No. 1,304,472, for Improvements in folding machines, granted May 20, 1919, on the application of P. R. Glass and reference may be had to this patent for a description of such parts of the machine as are not fully described herein.

Feeding of the work is accomplished by mechanism in the head of the machine and comprising an oscillating feed foot 30 (Fig. 4) operating upon the margin of the work, such as a sole 200 shown in Fig. 9, in a direction to cause the sole to be held in contact with the edge gage 20, thereby effecting a substantially automatic presentation of the margin of the sole to the operating tools. With this feed foot cooperates a reciprocating presser foot 32 which holds the work against the table during the intervals between the operation of the feed foot. The feed foot 30, which has a serrated lower end and an enlarged upper end 36 (Fig. 11), is clamped upon the lower end of a feed foot bar 34 by a screw 38. To produce a four-motion feed, this feed foot bar 34 is mounted for oscillatory and up-and-down movement in a recess formed in the rear

face of a cap 40 secured to the end of the frame arm 12 by screws 42 (Fig. 5). A slideway is formed partly by the cap and partly by a recess in the end of the arm 12 to receive a pivot-carrying slide 44 (Fig. 10). This slide is adjustably positioned, as will be described, and forms a bearing for a pivot stud 46 (Figs. 1 and 10) integral with a sleeve 48 in which the feed rod 34 slides up and down. The upper end of the rod passes through a bore in the side of a cam follower frame 50 (Fig. 5). This frame coacts with a cam 52 secured to a drive shaft 54. Interposed between the bottom of the cam follower frame 50 and a collar 56, clamped to the feed foot rod 34, is a spring 58 tending always to push the feed foot 30 into engagement with the work. The cam 52 imparts to the frame 50 a sidewise swinging movement and an up-and-down movement, the feed foot rod 34 being lifted by engagement of the frame 50 with a block 60 secured to the upper end of the rod 34. This block has a pin 62 which cooperates with the frame 50 to prevent twisting of the rod 34. Rotation of the cam 52 is thus effective to impart a four-motion feed to the foot 30. The extent of the feeding movement is determined by the position, heightwise of the head, of the pivot 46 journalled in the slide 44 and this latter may be adjusted manually by a bell crank 64 (Fig. 1) mounted inside the frame upon a stud 63 and held in position by a pin 66 passing through one of a series of apertures 67 provided in the frame. The lower arm of the bell crank is connected by a short link to the slide 44.

The presser foot 32 is L-shaped (Fig. 9) and is mounted upon a bracket 70 by means of a substantially horizontal pivot 71, extending in the general direction of the line of feed, thus allowing the foot to contact fully with the margin of a sole, regardless of whether the margin is flat or beveled. The bracket 70 (Fig. 5) has a head 72 (Fig. 6) which is clamped to the lower end of a sleeve 74 by means of a pinch screw 76. It will be seen from Fig. 3 that the sleeve 74 is slideable in a bore formed in the cap 40 and that it is prevented from turning with respect to the cap by a spline 77. A presser-foot rod 80 has a reduced lower end 81 extending through the sleeve 74 and provided with a retaining screw 82 at its lower end, while a spring 84 surrounding this reduced extension is interposed between a shoulder on the rod 80 and the upper end of the sleeve 74 thus tending to hold the presser foot in contact with the work until it is lifted out of engagement therewith by the head of the screw 82 coming into contact with the bottom of the sleeve 74. To lift the presser foot, the upper end of the rod 80 is secured to a cam follower frame 86 (Fig. 5) which surrounds an eccentric 88 attached to the end of the drive shaft 54. Upon rotation of the drive shaft, this eccentric 88 alternately lifts the presser foot away from the work and then allows it to move forcibly into engagement with the work under the pressure of the spring 84.

It will be noted that the block 72 has a lateral extension or ear 90 (Figs. 6 and 7) which is received in a slot 92 (Fig. 7) in the rear face of the cap 40 to facilitate lifting of the presser foot by means of a lever 94 having a finger piece 96 (Fig. 1), this lever being pivoted upon a stud 98 (Fig. 7) at the lower end of the cap 40. When the presser foot is raised manually by a depression of the finger piece 96, the outer end of the lever 94, which is received in a slot in the cap 40, engages the under side of the ear 90 upon the presser

foot bracket and lifts the foot out of engagement with the work to a position wherein it is held by a spring pressed latch 100 (Fig. 1). This latch may be released by the actuation of a treadle rod 102 which is used to start the machine. To this end, the treadle rod is connected to a bell crank 104, to the upper end of which is secured a rod 106 extending to a lever 108 pivoted on the stud 63 on which the bell crank 64 is mounted. On the side of this lever 108 is a pivoted block slidably receiving a rod 110 pivoted to the upper end of the latch 100. A nut upon the end of the rod 110 engages the pivoted block on the side of the lever 108 thereby to effect a positive disengagement of the latch 100 when the treadle rod 102 is raised. A spring is interposed between the other side of this pivoted block and a shoulder on the rod 110 thus allowing an independence of movement of the latch with respect to the block on the lever 108. The bell crank 104 is pinned to a pivot rod 112 passing through the frame 10 and secured by a set screw on the outer end of this rod 112 is a collar 114 in which is threaded a clutch actuating stud 116. A pin clutch 118 of any well-known type is interposed between the drive shaft 54 and a pulley 120, and a clutch actuating stop arm 122, which is normally pulled toward the shaft by a coiled spring 124, is provided with a depending cam surface 126 with which the pin 116 contacts as the treadle rod 102 is raised thereby to remove the stop arm 122 and allow the clutch to be closed and the machine to operate.

The cellulosic material which is to be applied and transformed into cement may be supplied in the form of tape, braid, or, as herein illustrated, in separate strands of loosely twisted yarn of acetate silk. If desired, some threads of cotton may be included which will not be affected by solvents such as are described herein, thus giving additional strength to the partially converted strip. As exemplified in the drawings, the textile material employed is a loosely twisted yarn from a suitable cellulose derivative, easily soluble in a readily available organic solvent to form cement. While cellulose esters and ethers, such as cellulose nitrate, cellulose acetate, ethyl cellulose and benzyl cellulose, may be used for this purpose, I have found particularly satisfactory the cellulose acetate yarn which is commercially available under the trade name "Acetate Silk."

In the illustrated machine, six strands of yarn 130 (Fig. 1) are supplied from spools 132 carried upon a suitable support 134 attached by cap screws 136 (Fig. 5) to the rear face of the overhanging frame arm 12. The strands pass from the spools loosely through a single guide opening 137 formed in an end 138 of one arm of a pull-off mechanism, to be described, and through individual openings in a guide 140 (Figs. 1 and 5) attached to the frame. The strands then pass through individual openings in an upper flange 142 and a lower flange 144 of a combined guide and presenter 146 which is pivotally mounted upon a stud 148 in the feed foot block 36. This presenter is notched at 150 (Figs. 4 and 5) to cooperate with a pin 152 thereby to allow limited pivotal movement about the stud 148 and is rotated clockwise, as viewed in Figs. 5 and 11, by a spring 154 coiled around the stud 148 and having an end which engages a pin 156 (Figs. 6 and 11) on the presenter. In general, the presenter operates to deliver several parallel strands of

yarn to the sole in exactly the desired position with respect to the edge of the sole.

On this presenter the perforated forward flange 144 is set at an acute angle to the face of the presenter plate 146 in order that it may be substantially at right angles (Fig. 9) to the line of feed as determined by the bulges 22, 24 of the edge gage 20. This is particularly important when rounding sharply curved portions, such as the toe, so that the line of the perforated flange 144 shall then be substantially radial with respect to said curved portion, thus insuring an even spacing of the strands along the margin of the sole and providing a stripe of resulting cement which is of substantially uniform width and is uniformly spaced from the edge of the sole for reasons set forth in describing the position of the nozzles of the machine for applying activating liquids described in my above mentioned application. The pull-off mechanism operates during the forward feeding movement of the feed foot 30. After this, the presser foot 32 descends and clamps the strands against the sole and then the feed foot carrier rises and moves to the right, as seen in Fig. 5, drawing the guide flanges 142 and 144 of the presenter along the loose strands of yarn preparatory to the reengagement of the feed foot with the sole in a new position. At the beginning of the operation, the projecting ends 160 (Fig. 11) of the strands 130 are pinched beneath the presser foot 32 and the yarn is delivered to the sole 200 by the oscillating movement of the presenter with the feed foot 30.

In order that the strands of yarn between the spools and the presenter may be relatively loose so that there will be no danger of the breakage of the strands during the oscillation of the presenter, the machine is provided with a pull-off mechanism, mentioned above, which intermittently draws the strands down from the spools. This mechanism, as best shown in Figs. 5 and 8, comprises an arm 162 pivoted upon a screw stud 164 threaded in the cap 40 and with the turned-over end portion 138 apertured at 137 to form a guide as has been already described. This arm is provided with a wear piece 166 which is held in contact with a cam 168 by a spring 170. The cam 168 is secured upon the end of the drive shaft 54. Cooperating with this arm 162 is another arm 172 which is also pivoted upon the stud 164. The upper end of this arm normally rests against a stop 174 screwed to the front side of the arm 12 and is held there resiliently by a spring 176. Upon the arm 162 is a cross-bar or gripper 178 (Fig. 2) and upon the arm 172 is a grooved cross flange or gripper 180. Two spaced pins 182 fastened in the cross-bar 178 pass loosely through holes in the flange 180. The strands of yarn, passing through the guide opening 137 in the upper end of the arm 162, are threaded between the pins 182 and thence through the openings in the fixed guide 140. As the cam 168 rotates, it moves the arm 162 toward the arm 172 and grips the strands of yarn between the bar 178 and the flange 180, and thence continues to move the arms together to cause the yarn to be drawn through the opening 137 by reason of its contact with the back side of the stop 174, as shown in Fig. 8, thus pulling off the yarn from the spools and providing some slack which will be taken up by the presenter 146 as the work is fed forward. The cam 168 alternately moves the arms 162, 172 into the position shown in Fig. 8 and then allows them to drop back into the position shown in Fig. 5 where the yarn is not gripped.

After a piece of work has been completed, the strands which have been attached to the sole must be severed from the supply strands and this is accomplished by means of a knife 190 pivotally mounted upon a reciprocating carrier 192 (Fig. 3) secured by a screw to the lower end of a rectangular knife bar 194 (Fig. 10). The pivotal mounting allows the knife to contact perfectly across the margin of the sole regardless of whether the sole is beveled or reduced at that point or is flat. The knife bar 194 is received in a rectangular groove in the rear face of the cap 40 and rests against the end face 196 of the arm 12. The knife bar 194 has a recess to receive a spring 198 (Fig. 3) abutting a plunger 202, the upper end of which rests against a stop flange 204 extending inwardly from a block 206 (Figs. 5 and 7) held on the head of the machine by a screw 208. This spring 198, therefore, tends to push the knife 190 into contact with the work. In order that the knife bar may be raised to compress the spring 198, the cap 40 is cut away at 210 (Fig. 7) to expose a laterally projecting stud screw 212 adapted to be raised by engagement with the cup 214 at the upper end of a finger 216 secured by a screw 218 to the outer end of the hand lever 94. This finger 216 is pulled inwardly toward the head by a spring 220 so that, when the finger piece 96 on the lever 94 is depressed, the cupped portion 214 of the finger 216 will engage the stud 212 and raise the knife bar. The knife bar will then be held in upper position by a latch 222 pivotally mounted in a slot (not shown) in the upper end of a block 224 attached to the cap 40. This latch is urged into operative position by a spring 226 attached at its upper end to the block 206 and at its lower end to the latch. A pin 228 upon the finger 216 is adapted to engage the upper side of the lower arm of the latch 222 thereby to release the latch when the finger piece 96 on the lever 94 is moved upwardly thereby pulling down on the pin 228. The machine stops with the feed foot raised and the presser foot down. The operator then moves the finger piece 96 upwardly to release the knife bar and cause the knife to sever the strands of yarn. As the knife bar descends, a rearwardly projecting finger 230 (Fig. 5) integral with the knife carrier 192 engages the presenter 146 and, by suitably shaped cam surfaces on these two parts, moves the presenter counterclockwise against the tension of the spring 154 until the lower side of the notch 150 engages the pin 152. This happens just before the knife cuts off the strands and serves to insure that there shall be projecting ends 160 of the strands of yarn 130 beyond the lower flange of the presenter ready for engagement beneath the presser foot, as shown in Fig. 11, as the next piece of work is brought into position. The operator will then depress the finger piece 96 on the lever 94 to reset the knife and in so doing will raise the presser foot, by engagement of the lever 94 with the lateral projection 90 upon the presser foot carrier, as previously described, against the tension of the spring 84.

It is desired to cause the strands of yarn to stick to the sole sufficiently, as soon as they are brought in contact therewith, to make sure that the strands are held in the proper position on the sole where they have been laid. It is also desired to soften or gelatinize the strands rapidly so that they are converted into a so-called "one-way" adhesive suitable for immediately attaching a sole to a lasted shoe. These results can best be obtained by the application of a sol-

vent, rendered viscous by the presence in it of a cementitious compound, to the roughened flesh surface of the sole, just ahead of the application of the strands of yarn thereto, thereby securing immediate adhesion of the yarn to the sole and also partly softening the acetate silk yarn, and by applying to the upper surface of the strands of yarn a low-viscosity solvent which will readily dissolve and gelatinize the cellulose ester of the yarn. An illustrative composition of the viscous type of softener, as disclosed in Letters Patent of the United States No. 1,959,321, granted May 15, 1934, upon an application filed in the name of Walter H. Wedger comprises

Nitrocellulose of 1100-seconds viscosity 40 grams
Denatured alcohol ----- 18 cc.
Acetone ----- 900 cc.

The machine is provided with a receptacle 232 (Fig. 1), supported on the frame by a bracket 20 attached by bolts 234 and provided with a plugged elbow 236 so that it may be filled or partially filled with a viscous solvent by removing the plug. Air under pressure is supplied from any convenient source through a pipe 238, a pressure reducing valve 240 having an adjusting handle 241, and past a pressure measuring gage 242. At the outlet end of the receptacle an outlet pipe 244 is provided with a turn valve 246 and the pipe terminates in a small capillary tube 248 of 30 greatly reduced diameter. The bore of this tube 248 will be of the order of forty-thousandths of an inch. With a tube of this size, there will be no dripping of the solvent when the valve is closed and the friction between the solvent and the walls of the tube will be sufficient to render the pressure uniform so that the quantity extruded upon the sole will be of a known amount. A receptacle 250 for a low-viscosity solvent, such as acetone, is structurally similar to a sight-feed oil cup. This receptacle is supported by a bracket 252 attached to the container 232 and has an outlet pipe 254 (Figs. 9 and 11) which terminates above the strands of yarn between the presenter 146 and the knife 190 and at about the point where the yarn is first brought into contact with the sole by the presser foot 32 but just to the rear thereof. This low-viscosity solvent will soften the fibers of the yarn and convert them rapidly into a cement by means of which the sole 50 may be attached to a shoe. Control of the quantity of solvent delivered to this tube 254 is effected by turning a knurled sleeve 256 (Fig. 1) at the top of the receptacle 250 as in similar oil cups and the flow may be allowed or may be shut off by 55 raising or lowering a needle valve 258, the upper end of which is pivoted to a lever 260 fulcrumed on a bracket at the top of the receptacle. The valves 246 and 258 may conveniently be controlled by connecting them to an actuating rod 60 262 to which may be attached a treadle rod 264. This actuating rod 262 is pivotally connected to an arm 266 secured to the turn valve 246 while the upper end of the bearing 262 is slotted at 268 so that the rather wide range of movement 65 required for opening the valve 246 will not interfere with the action of the needle valve 258 which needs only to be raised a small fraction of an inch. Control of the quantity of viscous solvent extruded may be effected by turning the handle 70 241 upon the reducing valve 240 and thereby varying the air pressure applied to the solvent in the receptacle 232.

In the use of the machine, the operator will present a piece of work, such as a sole 200, on the 75

table 16 with its edge against the gage 20. At this time the feed foot will be in raised position, the machine having been brought to rest in the position shown in Fig. 5 and the presser foot will 5 be held in raised position against the tension of this spring by the latch 100. The operator will then step on the treadle attached to the rod 264 to open the valve of the solvent containers and substantially simultaneously will actuate a treadle 10 to raise the rod 102 thereby to release the latch 100 and to close the clutch and start the rotation of the drive shaft 54. The forward movement of the sole as it is pushed over the table 16 in initially presenting it to the machine will have straightened out the loose ends 160 of the strands of 15 yarn to a position where they will lie beneath the presser foot 32 so that when the presser foot is dropped it will clamp the ends of these strands temporarily against the sole causing them to be "tacked" by the low-viscosity solvent from the receptacle 250 and the presenter 146 will deliver in exactly the desired position above the sole several parallel strands of yarn 20 ready for attachment thereto. The yarn will 25 become only partly softened at the time when the presser foot 32 engages it but the hammering action of the presser foot will serve to force the yarn firmly into contact with the roughened sole coated with the viscous solvent and at the same 30 time slightly to flatten the yarn wet by the low-viscosity solvent supplied through the tube 254. This action will continue until so much of the margin of the sole has been treated as is desired. The application of the yarn will be started approximately at the heel breast line upon one side and will continue around the toe of the sole up to approximately the heel breast line on the other side of the sole. When this stopping point is reached, the operator will release the treadles attached to the rods 264 and 102 stopping the flow 35 of solvent from the receptacles and the rotation of the drive shaft 54. The action of the clutch 118 will be to stop the drive shaft in a position such that the presser foot is down and the feed 40 foot is raised and moved back toward the operator ready to descend for the next feeding cycle, as shown in Fig. 5. The operator will then cause an upward movement of the finger piece 96 to release the latch 222 allowing the knife 190 to 45 drop against the partially softened threads and to cut them in two. As the knife descends and before it cuts the yarn, it will push aside the presenter 146 and draw out the free ends 160 beyond the flange 144 of the presenter because at that 50 time the yarn is still attached to the portion on the sole. This will prevent any possible sticking of the strands in the perforations of the guide flange 144 and will leave projecting dry ends of such length that the operation may be started 55 immediately upon the next sole without any effort on the part of the operator. The operator will then press down upon the finger piece 96, raising the presser foot through the engagement of the rearwardly projecting ear 90 and resetting the 60 knife. The presser foot will be held up in raised position by the already-in-position latch 100 while the knife will be retained by the latch 222.

Having described my invention, what I claim as new and desire to secure by Letters Patent of the 70 United States is:

1. In combination, means for treating a piece of textile material containing a cellulose derivative with a solvent for the cellulose derivative thereof thereby to convert at least a portion of the textile 75 material into an adhesive, and means for pro-

gressively and repeatedly hammering the treated textile material into contact with the work as the material is presented to the work.

2. In a machine for applying an adhesive to a piece of work, means for presenting thereto a 5 piece of textile material containing a cellulose derivative, means for applying to the textile material as it is being positioned upon the work a solvent for the cellulose derivative thereof, and means adjacent to said presenting means movable 10 toward and away from the work for substantially immediately pressing the material into contact with the work.

3. In combination, work feeding means including a presser foot movable toward and away from 15 the work, means for supporting a supply of elongated textile material containing a cellulose derivative, means for presenting said textile material to the work in advance of the presser foot, and means for supplying a solvent for the cellulose derivative in advance of the presser foot 20 whereby the movement of the presser foot toward the work causes the softened material to stick to the work.

4. In combination, means for feeding a piece of 25 work comprising a presser foot movable toward and away from the work, a guide for presenting to the work in advance of said presser foot elongated textile material containing a cellulose derivative, means for applying a solvent for said 30 cellulose derivative to said textile material in advance of the presser foot whereby the cellulose derivative is converted into an adhesive which is pressed into contact with the work by the presser foot. 35

5. In combination, means for applying progressively to a piece of work elongated textile material comprising a cellulose derivative, means for supporting a supply of the textile material, a guide interposed between said supply and said applying 40 means whereby to position the textile material with respect to the work, a movable cutter, means for moving the cutter, and means operated by the movement of said cutter for causing an unused length of textile material to project through 45 said guide. 55

6. In combination, work feeding means comprising a reciprocating presser foot and an oscillating feed foot, means for supporting a supply of textile material, a guide for the material resiliently mounted upon said feed foot, and means operable at the termination of the feeding movement for moving said guide upon the feed foot to cause an unused length of the textile material to project beyond the guide. 50

7. In combination, work feeding means comprising a reciprocating presser foot and an oscillating feed foot, one or more spools for supporting a supply of textile material, a guide for the material resiliently mounted upon said feed foot, 60 a movable cutting-off knife, and means operated by movement of said knife for moving said guide away from the presser foot to cause an unused length of the material to project beyond the guide. 65

8. In combination, in a machine for applying elongated textile material to a piece of work, a presser foot spring-urged into engagement with the work, a latch for holding said presser foot out of engagement with the work, a cutting-off 70 knife spring-urged into engagement with the work, a latch for holding said knife out of engagement with the work, and operator controlled means for lifting said presser foot and resetting said knife. 75

9. In combination, in a machine for applying elongated textile material to a piece of work, a presser foot spring-urged into engagement with the work, a latch for holding said presser foot out of engagement with the work, a cutting-off knife spring-urged into engagement with the work, a latch for holding said knife out of engagement with the work, and operator controlled means for lifting said presser foot and resetting said knife, said operator controlled means being constructed and arranged also to release said knife on movement in the opposite direction.

10. In combination, means for applying elongated textile material progressively to a piece of work, a spool for supporting a supply of textile material, a guide positioned adjacent to the work for presenting the textile material in a predetermined relation to the edge of the work, means for adhesively securing the textile material to the work, an intermittently operated pull-off acting upon the textile material between the spool and the guide to slacken the material, and means to operate said pull-off as the material is applied.

11. In combination, a work support, an edge guide, an intermittently operated presser foot, a feed foot, means for imparting a four-motion feed to said foot, means for supporting a supply of elongated textile material containing a cellulose derivative, a guide for said textile material mounted on said feed foot, a pull-off interposed between the supply supporting means and the guide, and means for delivering a solvent for the cellulose derivative to transform said textile material to an adhesive as it is applied to the work.

12. In a machine for applying an adhesive to a piece of work, means for presenting thereto a piece of textile material containing a cellulose derivative, means for applying an adhesive to one of said pieces to secure the textile material in position upon the work, and means for applying a solvent for the cellulose derivative to the textile material thereby to convert it into an adhesive.

13. In a machine for applying an adhesive to a piece of work, means for guiding to the work a piece of textile material containing a cellulose derivative, and a plurality of applying means positioned upon opposite sides of the textile material as it is presented to the work and constructed and arranged to apply an adhesive to one of said pieces in a position between the pieces and to apply a solvent for the textile material in another position.

14. In a machine for applying a strip of adhesive to a piece of work between which and the machine relative movement may be produced, a guide for directing to the work a piece of textile material containing a cellulose derivative, and a plurality of nozzles differently positioned with respect to the textile material and arranged to deliver thereto an adhesive and a solvent for the cellulose derivative.

15. In combination, means for applying elongated textile material containing a cellulose derivative progressively to a piece of work, means for delivering to the work in advance of the tex-

tile material a viscous solvent for said cellulose derivative, and means for applying to the upper surface of the textile material as it is applied to the work a low-viscosity solvent for the cellulose derivative whereby the textile material is secured to the work by the viscous solvent and is transformed into an adhesive by the combined action of the viscous and the low-viscosity solvents.

16. The method of applying an adhesive to a piece of work which consists in treating a strip of textile material containing a cellulose derivative in a fibrous, readily soluble form with a solvent for the cellulose derivative thereby converting at least a portion of the textile material into an adhesive, and progressively and repeatedly hammering the textile material into contact with the work as it is presented thereto.

17. The method of applying an adhesive to a piece of work which consists in presenting thereto a narrow piece of textile material containing a cellulose derivative in a fibrous, readily soluble form and which is readily distortable in all directions, applying a solvent for the cellulose derivative thereof to the textile material while it is being positioned upon the work, and substantially immediately pressing the material into contact with the work.

18. The method of applying an adhesive to a piece of work which consists in presenting thereto a textile material containing a cellulose derivative, securing the textile material in position upon the work by means of an adhesive, and applying a solvent for the cellulose derivative to convert it into an adhesive.

19. The method of applying an adhesive to a piece of work which consists in presenting thereto a textile material containing a cellulose derivative, securing the textile material in position upon the work by means of a viscous solvent for the cellulose derivative thereof, and applying additional solvent to facilitate the conversion of the cellulose derivative into an adhesive.

20. The method of applying an adhesive to a piece of work which consists in presenting to the work a piece of textile material containing a cellulose derivative, applying a viscous solvent for said cellulose derivative between the textile material and the work, thereby positioning said textile material upon the work, applying a low-viscosity solvent for the cellulose derivative to the already positioned textile material, and substantially immediately pressing the material into contact with the work.

21. The method of applying an adhesive to a piece of work which consists in presenting to the work a piece of textile material containing a cellulose derivative, coating that portion of the work which is to be occupied by the textile material with a viscous solvent for the cellulose derivative of said material, thereby to secure said textile material in position upon the work, and applying a low-viscosity solvent for the cellulose derivative to the already positioned textile material.
